(57) **CLAIM**

The ornamental design for a compact right angle driver, as shown and described.

DESCRIPTION

FIG. 1 is a front view of a compact right angle driver showing my new design.

FIG. 2 is a top plan view thereof.

FIG. 3 is a right side view thereof.

FIG. 4 is a left side view thereof.

FIG. 5 is a bottom plan view thereof; and,

FIG. 6 is a top right perspective view thereof.

The broken lines illustrate unclaimed structure on the compact right angle driver. The broken lines and structure they depict form no part of the claimed design.
